UNITED STATES PATENT OFFICE.

ALEXANDER WINTON, OF CLEVELAND, OHIO, ASSIGNOR TO WINTON GAS ENGINE AND MANUFACTURING COMPANY, OF CLEVELAND, OHIO.

VAPORIZING DEVICE.

1,116,192.

Specification of Letters Patent.

Patented Nov. 3, 1914.

Application filed February 24, 1913. Serial No. 750,287.

To all whom it may concern:

Be it known that I, ALEXANDER WINTON, a citizen of the United States, residing at Cleveland, in the county of Cuyahoga and State of Ohio, have invented certain new and useful Improvements in Vaporizing Devices, of which the following is a specification, reference being had therein to the accompanying drawing.

10 My invention relates to improvements in vaporizing devices.

The object of my invention is to provide a vaporizing device for internal combustion engines in which oil other than gasoline can 15 be very effectively used.

Another object of my invention is to provide a vaporizer of this character in which the amount of oil and air supplied thereto is controlled by a governor geared to the 20 engine.

A still further object of my invention is to provide a simple, cheap and more effective vaporizing device having certain details of structure, hereinafter fully set forth.

25 In the accompanying drawings: Figure 1 is a vertical sectional view of a vaporizer embodying my invention. Fig. 2 is a side elevation looking in the direction of the arrow Fig. 1.

30 Referring now to the drawings, 1 represents my improved vaporizing chamber having an outlet 2, leading to the inlet manifold of the engine, not shown. Within the vaporizer is arranged a balanced valve 3 having 35 beveled faces 4, and 5, coöperating with the valve seats 6, and 7, arranged within the vaporizer. The valve 3 is provided with two series of openings 8, and 9, arranged in a circular line, as clearly shown in Fig. 1 of 40 the drawings.

The lower end of the vaporizing chamber 1 is provided with a movable cap 10, to which is connected an oil-pipe 11, which communicates with a tube 12, carried by the 45 inner face thereof, said tube extending up about mid-way of the vaporizer within the balanced valve 3. The upper end of the vaporizer is provided with a movable cap 13, through which loosely passes a tube 14 of a 50 diameter greater than that of the tube 12, and extends approximately down to the lower cap 10. This tube 14, at its upper end, is provided with a series of openings 15 and

at its lower end with a series of openings 16, which communicate with the spaces 17 and 55 18 above and below the balanced valve 3.

The tube 14, at a point opposite the end of the tube 12, is provided with a series of openings 19, which communicate with the interior of the balanced valve 3. Extending 60 through the tube 14, from its upper end, is a valve stem 20, which extends downwardly through the tube and having a tapered lower end entering the oil supply tube 12, whereby the flow of oil from the tube 65 12, is controlled. This valve-stem 20 is screw-threaded within the tube 14, whereby it may be adjusted for regulating the flow of oil from the tube 12.

Carried by the upper face of the vaporizer is a lug 21, to which is pivotally connected a link 22, and pivotally carried by the upper end of the link is a yoke 23, which straddles the tube 14 and pivotally connected thereto. The yoke 23 is connected to the 75 lever 24, by means of a link 25. The lever 24 is connected to the speed governor 26, in such a position that when the engine slows down the weights 27 move inwardly, as is well understood by those skilled in the art. 80 The outer end of the lever 24 is raised which, through the medium of the link 25, and the yoke 23, the tube 14 and the valve-stem 20 are raised allowing more oil to flow from the tube 12. It is understood that the speed 85 governor is connected directly to the engine.

Connected to the oil tube 11, leading into the lower end of the vaporizer, is a pipe 28, which is connected to the float chamber 29, located adjacent the vaporizing chamber. 90 Located above the vaporizing chamber is an oil tank 30 and a gasoline tank 31. The oil tank 30 has a pipe 32 leading downwardly and connected to a coupling 33, which has a pipe connection 34 with the float chamber 95 29. The gasoline tank likewise has a pipe 35 leading downwardly and around the vaporizing chamber and connected to the coupling 33, whereby either oil or gasoline may enter the float chamber 29. The pipe 32 100 above the coupling 33 is provided with a stop-cock 36. The pipe 35 below the coupling 33 is likewise provided with a stop-cock 37, whereby, as heretofore stated, either oil or gasoline may be allowed to enter the 105 float chamber 29 through the pipe 34.

Air is allowed to enter the vaporizing chamber through the pipe 38. This pipe through which the air is fed to the vaporizer is coiled within the manifold 39, as shown in Fig. 1, whereby the air is heated and the oil is more quickly and thoroughly vaporized. This air-pipe 38 intermediate the vaporizing chamber and the exhaust manifold is provided with a pipe 40, having a stop-cock 41, whereby cold air may be allowed to pass into the vaporizer, or both cold and hot air together may pass thereto. The amount of cold air allowed to pass to the vaporizer chamber is regulated by the valve 41, as clearly shown in Fig. 1 of the drawings.

In operation the stop-cock 36 is turned so that no oil can pass from the tank 30 to the float chamber, but the cock 37 is turned so that the float chamber is supplied with gasoline from the tank 31. The engine is started in the usual manner and a charge of vapor or explosive mixture is sucked from the vaporizer 1, through the pipe 2 to the inlet manifold and thence to the engine cylinders. The oil passes from the float chamber 29 through the pipe 28 and the pipe 11 to the tube 12 and out through the upper end of the said tube. When the engine is at rest it will be understood that the speed-governor is in such a position that the tube 14 and the valve stem are raised so that a full flow of oil is allowed through the upper end of the tube 12. After the engine is started the weights 27 of the speed governor are thrown outwardly lowering the tube 14 and causing the valve stem 20 to gradually cut off the flow of oil through the upper end of the tube 12. The air passes through the pipe 38 into the spaces 17 and 18, above and below the balanced valve 3, through the openings 15 and 16 to the interior of the tube 14 and come in contact with the oil, as it passes from the tube 12. The air, oil and vapor passes from the tube 14 outwardly through openings 19 in the tube directly opposite to the end of the oil tube 12 into the hollow balance valve 3. The mixture then passes from the hollow valve through the openings 4 and 5, into the main vaporizing chamber, from which it is sucked through the pipe 2 to the inlet manifold, as heretofore described. After the engine has been heated up and the exhaust manifold thoroughly heated the cock 37 is turned off shutting off the gasoline and the cock 36 is opened so that the oil from the tank 30 passes into the float chamber, and thence to the vaporizer, as heretofore described. The exhaust manifold 39 having been thoroughly heated by the running of the engine on gasoline, it will be seen that the air which enters the vaporizing chamber is thoroughly heated by the exhaust manifold and thus the oil, preferably, kerosene is readily vaporized and the engine effectively run by the same.

Having thus described my invention, what I claim and desire to secure by Letters Patent is:—

1. A vaporizing device of the character described, comprising a vaporizing chamber, a float chamber in communication with the lower end of the vaporizing chamber and having a pipe extending up into the vaporizing chamber, a balanced valve controlling a flow of oil from the float chamber to the vaporizing chamber, an oil supply for the float chamber, a gasoline supply for the float chamber, separate valves controlling the oil and gasoline supply to the float chamber and an air supply passing through the exhaust manifold and communicating with the vaporizing chamber. 75 80

2. A vaporizing device of the character described, comprising a vaporizing chamber, a hollow balanced valve, means for operating said valve, an oil supply for the said chamber and extending upwardly within the hollow valve, and means for supplying air within the hollow balanced valve at the point of entrance of the oil thereto, and means for controlling the air to the hollow balanced valve. 85 90

3. A vaporizing device of the character described, comprising a vaporizing chamber, a hollow balanced valve within the chamber, an oil supply entering the lower end of the vaporizing chamber and passing upwardly into the hollow balanced valve, a tube surrounding the oil supply pipe and extending through the hollow balanced valve, and having openings in communication with the valve at a point opposite the upper end of the oil supply pipe, and means for supplying the tube with air at its upper and lower ends discharging it through the openings in the hollow valve, said valve having two series of openings discharging the oil and air into the vaporizing chamber. 100 105

4. A vaporizing device of the character described, comprising a vaporizing chamber, a gasoline supply for said chamber, an oil supply pipe extending through the lower end of the chamber and upwardly to a point about the center thereof, a balanced hollow valve surrounding the oil supply pipe, a tube surrounding the oil supply pipe and extending through the hollow balanced valve and having openings communicating with an air supply, said tube having openings at a point opposite the upper end of the supply pipe and communicating with the hollow balanced valve, said valve having two series of openings adapted to discharge the oil and vapor into the vaporizing chamber. 110 115 120

5. A vaporizing device of the character described, comprising a vaporizing chamber, an oil supply pipe for the chamber and extending upwardly within the vaporizing chamber, a balanced hollow valve surrounding the oil supply pipe, a tube extending 125 130

through the hollow balanced valve and surrounding the oil supply pipe and having openings above and below the valve, said tube having openings at a point opposite 5 the upper end of the oil supply pipe and communicating with the hollow balanced valve, said balanced valve having two series of openings to discharge the oil and vapor into the vaporizing chamber, and a valve 10 carried by the tube and extending downwardly therethrough and controlling the supply of oil from the upper end of the oil supply pipe.

6. A vaporizing device of the character 15 described, comprising a vaporizing chamber, an air supply chamber in communication with the vaporizing chamber at its upper and lower ends, valve seats arranged around said communications, a double hollow balanced valve resting on said valve seats and having two series of openings at its ends 20 communicating with the vaporizing chamber, an oil supply for said vaporizing chamber extending through the lower end thereof and passing into the balanced valve, a tube 25 carried by the valve and having a series of openings at its upper and lower ends communicating with the air chamber, said tube having a series of openings at a point opposite 30 the upper end of the oil supply pipe, a valve adjustably secured in the tube and adapted to enter the upper end of the oil supply pipe and controlling the flow of oil therefrom, and means controlled by the governor 35 for raising and lowering the balanced valve, whereby the oil supply from the oil supply pipe is controlled.

7. A vaporizing device of the character 40 described, comprising a vaporizing chamber, an air supply chamber at one side thereof and having communication at its upper and lower ends with the vaporizing chamber, valve seats surrounding said communications, a hollow double balanced valve resting 45 on said seats, an oil supply pipe extending upwardly through the air chamber and within the hollow balanced valve, a tube carried by the balanced valve extending therethrough and having openings communicating 50 with the air-chamber above and below the valve, said tube having openings at a point opposite the upper end of the oil supply pipe, a valve carried by the tube and extending into the upper end of the oil supply pipe for controlling the supply of oil 55 therefrom, means for adjusting said valve within the tube, a yoke surrounding the tube on the outside of the vaporizer and pivoted at one end, a lever connected to the said governor of the engine and having a link connection between its upper end and the yoke, whereby the slowing down of the engine forces the lever downwardly and raises the tube and the valve for allowing more oil to 60 be supplied to the vaporizing chamber.

8. A vaporizing device of the character described, comprising a vaporizing chamber, a double balanced valve within the chamber, an oil supply extending within the double balanced valve, an air supply for one 70 end of the chamber and adapted to pass through the double balanced valve, a valve carried by the double balanced valve and adapted to control the oil supply, and means operated by the governor on the engine for 75 operating said valve, whereby the oil and air supply are simultaneously controlled.

9. A vaporizing device of the character described, comprising a vaporizing chamber, a double balanced hollow valve controlling the 80 air supply through said chamber, an oil supply extending upwardly within the hollow balanced valve and terminating midway its end, means carried by the balanced valve for controlling the oil supply, and 85 means for discharging the air from one side of the chamber through the hollow balanced valve across the open end of the oil supply, and means connected to the opposite side of the vaporizing chamber for conveying the 90 vapor therefrom to the manifold of an engine.

10. A vaporizing device of the character described, comprising a vaporizing chamber, a hollow balanced valve dividing the vaporizing chamber into two compartments, an oil supply extending upwardly through the vaporizing chamber and terminating in the hollow balanced valve midway its length, an air supply to the vaporizing chamber, a 95 valve carried by the hollow balanced valve and controlling the oil supply, and means governed by the engine for controlling the hollow balanced valve, whereby the oil and air supply is automatically governed. 100

11. A vaporizing device of the character described, comprising a vaporizing chamber, a hollow valve within said chamber, an oil supply discharging within said hollow valve, an air supply for the center of said 110 valve said valve having air discharge openings at both ends substantially as shown and described.

12. A vaporizing device of the character described, comprising a vaporizing chamber, a hollow balanced valve within said chamber and oil supply discharging into said hollow valve at a point midway its hollow ends, an air supply for the center of the valve 115 and said valve having discharge openings 120 at both ends for discharging the mixture from the hollow valve.

13. A device of the character described, comprising a vaporizing chamber, a hollow double balanced valve within said chamber, an oil supply discharging into said hollow valve midway its ends, an air supply for 125 said valve at the center thereof and having discharge openings at the ends, means carried by the valve for controlling the oil 130

supply, and automatic means for controlling said hollow double balanced valve.

14. A vaporizing device of the character described, comprising a vaporizing chamber, a hollow double balanced valve within said chamber, an oil supply discharging at the center of the said hollow double balanced valve, an air supply at the center of said valve, said valve having discharge openings 10 at the ends arranged to be closed when the valve is seated, means carried by the valve for controlling the oil supply discharge, and automatic means for controlling the said hollow double balanced valve, substantially 15 as shown and described.
15. A vaporizing device of the character described, comprising a vaporizing chamber, a hollow valve within said chamber and having its opposite ends resting upon seats 20 within the chamber, an oil-supply discharging within the center of said hollow valve, means for supplying air to the center of the valve at a point of the discharge of the oil and means carried by the valve for controlling the oil supply, whereby the movement of the hollow valve simultaneously controls the air and oil.
16. A vaporizing device of the character

described, comprising a vaporizing chamber, a hollow valve within said chamber, an oil supply discharging within said hollow valve, valve seats at both ends of the valve and upon which the same is adapted to rest, means carried by the valve for controlling the oil supply, and automatic means for moving the valve, whereby the air and oil supplies are simultaneously controlled.

17. A vaporizing device of the character described, comprising a vaporizing chamber, a hollow valve within said chamber and having its upper and lower ends resting upon the seats within the chamber, an oil supply in the center of said valve, said valve having discharge openings adapted to be closed by the seats, means carried by the valve for controlling the oil supply, and means for moving the valve whereby the valve is moved for simultaneously controlling the oil-supply and the discharge of mixture from the chamber.

In testimony whereof I hereunto affix my signature in the presence of two witnesses.

ALEXANDER WINTON.
